UNITED STATES PATENT OFFICE.

IRVING F. WEBB, OF ELIZABETH, NEW JERSEY, ASSIGNOR TO THE SINGER MANUFACTURING COMPANY, OF ELIZABETH, NEW JERSEY, A CORPORATION OF NEW JERSEY.

SHAFT COUPLING.

Application filed December 7, 1920. Serial No. 428,866.

To all whom it may concern:

Be it known that I, IRVING F. WEBB, a citizen of the United States, residing at Elizabeth, in the county of Union and State of New Jersey, have invented certain new and useful Improvements in Shaft Couplings, of which the following is a specification, reference being had therein to the accompanying drawings.

10 This invention relates to shaft-couplings of the clutch-roll type and has for an object to provide an improved and simplified shaft coupling which may be easily assembled and taken apart without the exercise of particular care and attention to prevent misplacement or loss of the clutch-roll or rolls. Further objects of the invention will appear from the following description and claims.

The invention, as embodied in a shaft-coupling, comprises a hollow cylindrical member adapted to be entered by abutted shaft sections and having at each end an eccentric chamber. Each shaft-section has mounted thereon a clutch-roll which may be assembled

25 in operative position relative to the shaft-section before the shaft-section is inserted in the hollow cylindrical member. The shaft-section has fixed thereto a clutch-roll carrier which may be in the form of a collar fitted to a relatively large concentric chamber in the hollow coupling member. The collar forms the support for the clutch-roll which has its opposite reduced ends journaled in apertures in the inner face of the collar and a cheek-piece held in spaced relation to the inner face of the collar by suitable supporting means mounted on the latter. The concentric chamber which receives the collar, being as large or larger than the eccentric chamber, permits insertion or removal of the shaft-section, collar and clutch-roll, as a unitary assembly.

In the accompanying drawings, Fig. 1 is a longitudinal sectional view of the coupling device as embodied in a shaft-coupling. Fig. 2 is a transverse sectional view on the line 2-2, Fig. 1.

As represented in the drawings, the coupling member 1 is in the form of a hollow cylinder having inner and outer concentric chambers 2 and 3, respectively, and the intermediate eccentric chambers 4. The chambers 2, which are in reality merged into a single chamber, slidably receive the abutted ends of the shaft-sections 5. The outer con-

centric chambers 3 are larger than the chambers 2 and 4 and slidably receive the collars 6 which are preferably fixed by set-screws 7 to the shaft-sections 5. Disposed within the eccentric chambers 4 are the clutch-rolls 8. 60 These rolls are preferably each carried by a corresponding collar 6 and may be assembled in correct position on the respective shaft-section before such shaft-section is inserted in the hollow member 1. When the 65 shaft-section is removed, the collar 6 and clutch-roll 8 come with it and there is no danger of the clutch-roll 8 dropping out of the hollow member 1 and being lost.

The clutch-roll 8 may conveniently be 70 mounted on the collar 6 by providing the latter with a pair of spaced supporting pins 9 projecting into the eccentric chamber 4 and carrying at their free ends the cheek-piece 10. The cheek-piece 10 and the inner 75 face of the collar 6 are formed with opposed apertures 11 loosely receiving the trunnions 12 formed at the opposite ends of the clutch-rolls.

It will be evident that when the direction 80 of rotation of the shaft 5 is reversed, the shaft will be unlocked from the hollow member 1 and, since the clutch-roll is mounted firmly on the shaft, it follows that a minimum turning movement of the shaft is required to carry the roll to a position locking 85 the shaft to the hollow member for rotation in the opposite direction.

It is important that the clutch-roll chambers be open at their ends adjacent the ends 90 of the body member, as this feature, in conjunction with the clutch-rolls, which are connected to turn with the shaft-sections, permits of the assembling of the clutch-rolls on the shaft-sections preparatory to insertion 95 of the latter in the body member.

Having thus set forth the nature of the invention, what I claim herein is—

1. In a coupling device, the combination with a hollow member having concentric and eccentric chambers, of a shaft-section entering said chambers, a clutch-element carrier tightly secured to said shaft, and a clutch-element mounted on said carrier and removable from and replaceable in said carrier 100 and eccentric chamber together with said shaft as a unitary assembly.

2. In a coupling device, the combination with a member having inner and outer concentric cylindrical chambers of relatively 110

small and large diameter, respectively, and an intermediate cylindrical chamber eccentric to said concentric chambers of a shaft fitting said inner chamber, a collar fitting 5 said outer chamber, a screw for tightly securing said collar to said shaft, and a clutch-roll rotatably carried by said collar and positioned between said shaft and the wall of said eccentric chamber.

10 3. In a coupling device, the combination with a member having inner and outer concentric chambers of relatively small and large diameter, respectively, and an intermediate eccentric chamber, of a shaft fitting 15 said inner chamber, a collar secured to said shaft and fitting said outer chamber, supporting means fixed to said collar and projecting into said eccentric chamber, a cheek-piece carried by said supporting means, and a solid clutch-roll journaled 20 between said cheek-piece and the inner face of

said collar and positioned between said shaft and the wall of said eccentric chamber.

4. In a coupling device, the combination 25 of a body member having a shaft aperture and an eccentric clutch-roll chamber adjacent the shaft aperture and open at its end adjacent the end of the body member, of a clutch-roll adapted to be received in said 30 chamber, and means for holding said clutch-roll in assembled relation with said shaft section preparatory to insertion of the latter in the body member, said means being secured to rotate with the said shaft and carry the clutch-roll into wedging relation between the shaft and the wall of the clutch-roll chamber.

In testimony whereof, I have signed my name to this specification.

IRVING F. WEBB.

Certificate of Correction.

It is hereby certified that in Letters Patent No. 1,493,582, granted May 13, 1924, upon the application of Irving F. Webb, of Elizabeth, New Jersey, for an improvement in "Shaft Couplings," an error appears in the printed specification requiring correction as follows: Page 1, after line 96 insert the paragraph—

The invention is not, of course, limited to its use in duplicate for coupling abutted shaft-sections, but may be used for coupling the shaft to a hollow member of any of the various types commonly used in machinery.;
and that the said Letters Patent should be read with this correction therein that the same may conform to the record of the case in the Patent Office.

Signed and sealed this 15th day of July, A. D. 1924.

[SEAL.]

THOMAS E. ROBERTSON,
Commissioner of Patents.
